MEANS FOR FLOWING WELLS

Charles S. Crickmer, Dallas, Tex., assignor to
Merla Tool Company, Dallas, Tex., a firm of
Texas

Application December 21, 1936, Serial No. 116,937

15 Claims. (Cl. 103—232)

This invention relates to new and useful improvements in means for flowing wells.

One object of the invention is to provide an improved means for lifting well liquids by means of an auxiliary lifting medium, such as gas or air.

An important object of the invention is to provide an improved means for flowing wells which is actuated by a differential in pressure between the well liquid within the well tubing and the pressure of the lifting fluid in the well casing; said means being constructed so that a low well liquid pressure will operate the same, whereby the liquid pressure need not exceed the lifting fluid pressure at any time which makes the invention particularly adaptable for use on wells having a comparatively low standing liquid level and a resultant low pressure.

A particular object of the invention is to provide an improved apparatus for flowing wells which includes means for automatically and intermittently admitting lifting fluid under pressure into the liquid column in a well tubing to lift the column, the admittance of the fluid occurring when the liquid pressure has reached a predetermined point never equal to or in excess of the pressure of the lifting fluid.

Another object of the invention is to provide an improved flow valve for controlling the admittance of a lifting fluid from a well casing to a well tubing, said valve being constructed so that when in an open position, it exposes equal areas on both sides thereof, whereby it is balanced, and is moved to its closed position when the velocity of the lifting fluid flowing thereby reaches a predetermined point; and when the valve is in its closed position unequal areas are exposed on each side thereof, whereby the valve may be opened by a pressure less than the pressure holding said valve closed, which permits the valve to be opened by the well liquid pressure when said pressure is lower than the pressure of the lifting fluid.

Another object of the invention is to provide an improved system of flowing wells which consists in admitting a lifting fluid into the well tubing before the pressure of the well influent equals the pressure of the lifting fluid, and then cutting off the admission of the lifting fluid when the velocity of said fluid reaches a predetermined point, whereby the action is entirely automatic.

Still another object of the invention is to provide an improved system which consists in intermittently admitting a lifting fluid into the well tubing to raise the well liquid therein, the ad-

mission occurring when the liquid pressure in the tubing reaches a predetermined proportion of the pressure of the lifting fluid.

A very important object of the invention is to provide an improved flow valve including a movable piston for controlling the flow of lifting fluid from the well casing to the well tubing, said piston normally exposing equal areas to the lifting fluid when in an open position whereby the piston is balanced; the valve also including a second piston which has one end exposed to the pressure of the well liquid and its other end adapted to engage one end of the first piston when said first piston is in a closed position, the second piston having a larger cross-sectional area, whereby this increased area acted upon by the well pressure is transferred to one end of the first piston, so that unequal areas are exposed by the first piston to the lifting fluid and well liquid pressures whereby said piston is again moved to its open position by the differential therebetween.

Still another object of the invention is to provide an improved flow valve which is actuated by the differential in pressure of the well liquid within the tubing and the pressure of the lifting fluid in the well casing, and which is so arranged that the differential necessary to actuate the valve may be positively controlled.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in section and partly in elevation of a well casing and tubing and having flow valves, constructed in accordance with the invention, connected in the tubing string.

Figure 2 is a view, partly in elevation and partly in section of the valve, and showing the valve in its operative position.

Figures 3, 4 and 5 are enlarged, vertical sectional views of the valve, showing the various operating positions of the same.

Figure 6 is an enlarged, horizontal, cross-sectional view, taken on the line 6—6 of Figure 2.

Figure 7 is an enlarged, horizontal, cross-sectional view, taken on the line 7—7 of Figure 2.

Figure 8 is an enlarged, horizontal, cross-sectional view, taken on the line 8—8 of Figure 2.

Figure 9 is a transverse, vertical, sectional view of a modified form of the invention,

Figures 10 and 11 are similar views, showing the various operating positions of the valve,

Figure 12 is a view, similar to Figure 2, showing a slightly modified form of the valve, and

Figure 13 is a similar view with the valve in its shut off position.

In the drawings (Figure 1), the numeral 10 designates the well casing of an oil well. This casing extends downwardly substantially the length of the hole in the usual way and has a suitable casing head 11 at its upper end which is at the well surface. The head is provided with an inlet 12 whereby gas or other lifting fluid may be introduced into the casing.

Suspended axially from the casing head is the tubing string 13 having the usual screen 14 at its lower end. The lower end of the casing is packed off from the tubing by a suitable packer 15, whereby gas introduced into the casing at the surface of the well cannot pass downwardly thereby. All of the above parts are of the usual construction and are, therefore, subject to variation.

In carrying out the invention, a plurality of flow valves A are mounted at various stages in the tubing string 13. The valves control the flow of the gas, or other lifting fluid from the well casing into the tubing. Since the well liquid enters the tubing through the screen 14 at the bottom of the hole below the packer, it is obvious that the gas introduced into the tubing will aid in lifting the liquid to the surface by aerating the fluid column. It is noted that the number of flow valves which are employed is subject to variation because the number of flow valves depends entirely upon the condition of the particular well. In some instances, a single valve located near the lower end of the tubing string may be found sufficient to raise the liquid within the tubing. These instances would occur in wells having a comparatively low liquid level standing therein.

Each valve A includes an upper cylinder 16 and a lower cylinder 17 which are connected together by a coupling sleeve 18. The lower end of the bore 16' of the cylinder 16 is internally screw threaded while the upper end of the bore 17' of the lower cylinder 17 is similarly screw threaded to receive nipples 19 provided at the ends of the sleeve 18, whereby the cylinders and sleeve form an integral structure. It is noted that the bore 18' of the sleeve 18 has a smaller diameter than either of the bores of the cylinders. The provision of the connecting sleeve for the cylinders makes for easy assembling and dismantling of the device but if desired, these three members may be made in one piece.

The upper end of the cylinder 16 is provided with an upwardly extending nipple which is adapted to be screw threaded into a socket 20 which is formed at the lower end of a sleeve member 21. The bore 21' of this member has a smaller diameter than the diameter of the bore of the cylinder 16. The extreme upper end of the member 21 is formed with a screw threaded nipple 22 which is received within an opening 23 in the underside of a radially extending boss 24 formed on the tubing 13. The boss is preferably made integral with the tubing but may be welded, or otherwise secured thereto. The boss is formed with an angular passage or port 25 which leads from the upper end of the bore of the sleeve member 21 to the interior of the well tubing 13, whereby communication is established between the interior of the tubing and the member 21.

From the above, it will be seen that the cylin-

ders 16 and 17, as well as the sleeve 18 and member 21, are suspended from the boss 24 and extend vertically in parallel relation to the exterior of the tubing string 13. For supporting the lower end of the assembly, a similar boss 26 projects radially from the tubing and is disposed at a point below the lower end of the cylinder 17. A supporting screw 27 is screw threaded through an opening 28 provided in the boss 26 and has its upper end engaging in an axial recess 29 which is provided in the underside of the cylinder 17. By loosening the screw 27 so as to disengage the same from the recess 29 and then by unscrewing the nipple 23 at the upper end of the member 21, it will be obvious that the entire assembly may be readily removed from its position between the bosses 24 and 26. Similarly the assembly may be readily positioned on the well tubing.

The bore 18' of the sleeve 18 is slightly enlarged near its upper end to form a chamber 30 within said sleeve. The upper end of this chamber is closed except for an axial opening 31, which opening has a diameter smaller than the diameter of the bore 18'. Radial ports 32 extend through the wall of the sleeve 18 and communicate with the interior of the chamber 30. With this arrangement, it will be obvious that the gas or other lifting fluid within the well casing can flow through the ports 32 and into the chamber 30. From the chamber, such fluid may pass upwardly through the opening 31 and into the upper cylinder 16. A piston 33, preferably solid in cross section has its upper end slidable in the bore 18' of the sleeve 18, while the lower end of said piston projects downwardly within the lower cylinder 17. The piston has a plurality of labyrinth grooves 34 in its outer surface and is also provided with an annular flange 35 at its lower end. A lug 36 is located axially at the bottom of the piston.

The piston is normally held in its lowered position by a coiled spring 37 which surrounds the lower end of the piston and is confined between the annular flange 35 and the lower end of the sleeve 18. The bottom of the cylinder 17 has a pair of vertical ports 38 extending therethrough whereby communication is established between the interior of the cylinder 17 and the well casing. Therefore, the pressure of the lifting fluid within the well casing is exerted against the underside of the piston 33 at all times. The upper end of the piston 33 is reduced to form a head 39, which head is located within the chamber 30 when the piston is in its lowermost position. The head is formed with an annular valve seat 40 near its upper end and a reduced conical pin 41 extends upwardly from said seat. With the piston in its lowermost position and the head 39 within the chamber 30, the conical pin 41 has its upper end just below the axial opening 31 in the top of the sleeve 18, whereby the lifting fluid within the well casing may flow through the ports 32, chamber 30 and through the opening 31. It is pointed out that both the upper and lower ends of the piston 33 are exposed to the fluid pressure within the well casing and, therefore, the pressures exerted against both the upper and lower ends of said piston are substantially equal, whereby the piston is in a balanced state. The coiled spring 37 which surrounds the lower end of the piston is, of course, exerting its pressure to hold the piston in its lowermost position and, therefore, it is the pressure of this spring which overcomes the balanced condition of the piston to normally hold said piston lowered.

The bore 18' of the upper cylinder 16 is slightly

reduced at its upper end whereby an annular internal shoulder 16a is formed at substantially mid-height of the cylinder 16. A tubular piston or velocity tube 42 is mounted to reciprocate vertically within the reduced portion of the bore of said cylinder. The tube has a plurality of labyrinth grooves 43 in its outer surface and is also provided with an enlarged valve or head 44 at its lower end. The valve 44 is arranged to seat on top of the sleeve 18 and is preferably conical so as to enter the opening 31. When the valve is engaging the top of the sleeve, it will be evident that the opening 31 is closed. The valve is normally held in a seated position with the piston or tube 42 in its lowermost position by a coiled spring 45 which surrounds the lower end of the tube and is confined between the enlarged valve head 44 and the internal annular shoulder 16a within the cylinder 16.

When the piston or velocity tube 42 is raised by means of the pressure of the lifting fluid acting against its bottom, as will be explained, the fluid will, of course, pass through the openings 31 and into the interior of the cylinder 16. From the lower end of the bore of the cylinder, the lifting fluid will flow through inclined ports 46 which extend through the valve head 44 and then into the bore 42' of the tube 42.

The upper end of the bore 42' of the piston or tube 42 is normally closed by a metering pin 47 which is slideable vertically in the bore 21' of the sleeve member 21. The pin is provided with an external annular seat 48 arranged to engage the upper end of the piston 42 to close the bore thereof as clearly shown in Figure 1. That portion of the pin below the valve seat is tapered and when said seat is engaging the tube this tapered portion is located within the bore 42'. The portion of the pin above the seat 48 is tubular, being open at its upper end. The interior of this portion of the pin communicates with the bore 16' of the cylinder 16 by means of radial ports 49 provided in the wall of the metering pin 47.

Normally, with no pressure in the well casing 10, the pin is in the position shown in Figure 2 with its seat 48 engaging the upper end of the piston 42. It is held so by its own weight. The bore 21' of the member 21 within which the metering pin 47 is slideable, is enlarged near its upper end to form a chamber 50 within the member 21. That portion of the bore of the member 21 above this chamber is reduced as shown at 21a whereby an annular shoulder 51 is provided within the member 21 directly below this reduced portion. When the metering pin 47 is unseated and moved upwardly within the bore 21', as will be explained, its upper end will strike the annular shoulder 51 which acts as a stop to limit the upward movement of said pin.

From the above, it will be seen that the fluid which has entered the tubular piston or tube 42 when the valve head 44 has been unseated to admit fluid into the cylinder 16 and tube 42, the pressure of this fluid will overcome the weight of the metering pin to move the same upwardly against the shoulder 51, whereby the bore 42' is open. The fluid may then flow into the upper end of the cylinder 16 and into the socket 20 at the lower end of the member 21. When the metering pin 47 moves upwardly against the shoulder 51, as shown in Figure 3, the fluid may enter the ports 49 in the metering pin, flow through the bore of said pin and into the reduced portion 21a of the bore of the member 21. From the member 21 this fluid can then enter the

angular passage 25 in the boss 24 and thus flow into the tubing 13 wherein the liquid column is standing. Thus, it will be seen that when the lower piston 33 is in its lowered position, and the tubular piston 42 as well as the metering pin 47 are in their raised positions, the lifting fluid such as gas or air in the well casing may flow through the ports 32, chamber 30, opening 31 and into the upper cylinder 16. From this cylinder the lifting fluid enters the tubular piston 42, then flows through the port 49 in the metering pin 47, then through the bore of said pin and finally to the angular port 25, from where it enters the tubing 13. Therefore, a direct communication between the well casing and the well tubing is established.

In operation, it will be assumed that there is a liquid column standing within the well tubing 13 and that the auxiliary lifting medium, such as gas or air, has not been introduced into the well casing. The parts will be in the position shown in Figure 2 because obviously the pressure of the liquid within the tubing 13 will be exerted downwardly against the metering pin 47 and also against the projected area of the upper piston 42. The lower piston 33 will, of course, be in its lowered position because of the coiled spring 37 which is holding it so. As the lifting fluid is introduced into the well casing, it will, of course, completely fill the annular space between the casing 10 and the well tubing 13. The fluid will enter the port 32 in the connecting sleeve 18 and will also enter the port or opening 38 in the bottom of the lower cylinder 11. Upon entering through the port 32 into the chamber 30 it will be seen that the pressure of the fluid will be exerted against the upper area of the lower piston 33 and similarly by entering the ports 38 in the bottom of the cylinder 11, the fluid pressure will also be exerted against the lower end of the piston. Therefore, the lower piston 33 will be more or less balanced, which balance is overcome by the tension of the coiled spring 37 holding the piston in its lowermost position, with the conical pin 41 at the extreme upper end of said piston at a point below the opening 31. The fluid pressure within the chamber 30 will, of course, be exerted against the projected area of the valve head 44 on the upper piston 42, which area is exposed within the opening 31. This fluid pressure acting against this area will be acting against the weight of the piston 42, the weight of the metering pin 47, and the pressure of the coiled spring 35 plus the pressure of the liquid column which is, of course, acting on the projected area above the piston 42 and the pin 47. Obviously, the area above the piston 42 and pin 47 which is subjected to the pressure of the liquid column within the tubing 13 is greater than the exposed area of the valve head upon which the fluid pressure is acting. Therefore, it will take a greater pressure of the lifting fluid to raise the piston 42 than would be necessary if equal areas were exposed on each side of said piston.

Assuming for purposes of illustration, that the pressure of the liquid within the tubing is 50 pounds and the projected area upon which said liquid is acting is twice as great as the area upon which the fluid pressure is acting, then it follows that the fluid pressure would have to double the amount of the liquid pressure before the piston 42 could be unseated to uncover the opening 31. Therefore, by controlling the areas exposed on each side of the piston 42, it is possible to definitely control the exact pressure differential which is necessary to actuate or raise

said piston. When the fluid pressure within the casing has reached its predetermined point, it will raise the piston 42 so as to uncover the opening 31 and immediately the fluid may then enter the lower end of the bore 16' of the upper cylinder 16. As the piston 42 begins to move upwardly, the coiled spring 45 is, of course, compressed. Upon entering the cylinder 16 the fluid will immediately pass through the openings 46 and into the bore 42' of the piston 42. Since the only thing that is holding the metering pin 47 seated on the upper end of the piston 42 is the weight of said metering pin 47 and the liquid pressure in the tubing, the fluid pressure will immediately move said pin upwardly to its highest position which is in engagement with the annular shoulder 51 within the member 21. The fluid then passes through the openings or ports 49, through the pin 47 and then through the angular port 25 into the tubing 13. The fluid entering the tubing will aerate the liquid column therein and will raise the same to the surface of the well.

After the metering pin 47 has been raised against the shoulder as described, the fluid rushing through the tubular piston 42 and also acting against the underside of the entire area of the valve head 44 will raise the piston 42 to its highest position under tension of the coiled spring 45. This highest position of the piston 42 is limited by a shoulder 20' which is formed at the intersection of the bore 21' of the member 21 and the socket 20 at the lower end of said member. When the velocity tube or piston 42 strikes this shoulder 20' (Figure 3) its further upward movement is prevented. It is noted that when the piston has moved to this position it has not reengaged the annular seat 48 of the metering pin 47 and the escape of fluid from the bore 42' of said piston may continue. Therefore, once the metering pin 47 has moved to its uppermost position, it cannot again close the bore 42' of the upper piston until both members have begun their downward movement. It is noted that while the piston 42 is moving upwardly with relation to the metering pin which has previously been moved to its highest position, the tapered portion of the pin again enters the bore 42' whereby the flow of fluid from said bore is gradually metered as the piston 42 continues to rise.

While the metering pin 47 and the upper piston 42 have been moving to the position shown in Figure 3, as has been described, the lower piston 33 has remained inactive because the pressure on each side thereof is substantially equal. However, as soon as the piston 42 has moved to its highest position, and the liquid column in the tubing 13 has lightened, the velocity of the lifting fluid flowing through the openings 31 increases. This increase in velocity will, of course, lower the pressure within the chamber 30 accordingly and when this pressure reaches a predetermined point, the pressure below the piston 33 which remains constant, overcomes the tension of the spring 37 and raises the lower piston 33 to the position shown in Figure 4. In such position the conical pin 41 at the extreme upper end of the piston enters the opening 31 and the annular valve 40 engages the underside of the top of the sleeve 18 to close the opening 31 and thereby cut off the flow of fluid therethrough. After the lower piston has moved to this position (Figure 4), no more lifting fluid can enter the well tubing 13.

As soon as the lower piston 33 closes the opening 31, the fluid pressure below the upper piston 42 falls immediately and permits the spring 45 to lower the piston 42 to the position shown in Figure 5 so that the valve head 44 engages the upper end of the pin 41 on the lower piston. The spring does not have sufficient strength to overcome the pressure of the fluid below the piston 33 and, therefore, the pin holds the upper piston 42 in this position. Upon lowering of the piston 42, the metering pin 47 drops so that its seat 48 engages the top of said piston as it did previously. The parts remain in this position until such time as the liquid column builds up in the tubing 13. As this liquid column builds up, the pressure within the tubing is, of course, built up and this pressure is exerted on the projected area of the metering pin 47 tending to force the same downwardly. Due to the fact that the fluid pressure is within the chamber 30 surrounding the head 40 of the lower piston, the only area of said lower piston upon which the fluid is acting is the cross-sectional area of the opening 31, which is much smaller than the projected area upon which the liquid pressure is acting. Therefore, the pressure of the liquid column within the well tubing need never equal or be in excess of the pressure of the fluid within the well casing in order to force the piston 33 downwardly against the fluid pressure. Just how much pressure the liquid must build up with relation to the pressure of the fluid within the well casing is dependent upon the particular areas exposed to each of these pressures. Whenever the pressure of the liquid column reaches this predetermined point, it will force the metering pin 47 and upper piston 42 downwardly as a unit, which will force the piston 33 downwardly so as to disengage the valve 40 from the opening 31. This uncovers the opening 31 and immediately the fluid may again pass through the port 31 and into the cylinder 16 to again raise the metering pin 47 and upper piston 42 as has been explained. The cycle of operation is then repeated as above.

It is noted that after the original upward movement of the upper piston 42 upon the introduction of the lifting fluid into the casing 10, the valve head 44 at the lower end of said piston will probably not be again seated to close the opening 31 until the fluid pressure in the casing is entirely cut off. This is true because after having moved upwardly to the position shown in Figures 3 and 4, its immediate reengagement with the seat is prevented by the pin 41 which has moved into the opening 31 as shown in Figure 5. As soon as the pressure of the liquid in the tubing builds up sufficiently to force the lower piston downwardly, the port 31 is opened and more lifting fluid admitted, whereby the upper piston is again returned to the positions shown in Figure 4. Therefore, under ordinary operating positions, the upper piston 42 fluctuates constantly within its cylinder. The main function of this upper piston is to transfer an increased projected area to the lower piston 33, when said piston is closing the inlet of lifting fluid, whereby a greater area is exposed to the pressure of the liquid in the tubing than is exposed to the pressure of the lifting fluid, when the lower piston 33 is in a raised position, as shown in Figure 5. The upper piston will, of course, act as a check valve to prevent escape of liquid from the tubing into the well casing when there is no pressure in the well casing. It is noted that although the

springs 37 and 48 have been shown surrounding the pistons 34 and 42 respectively, these springs merely insure the positive movement of the pistons to their lowered positions. It has been found in actual practice that these springs could be eliminated and the pistons efficiently actuated solely by the pressure differentials.

From the above, it will be obvious that a valve which is intermittently operated by the differential in pressure between the liquid within the well tubing and the fluid within the well casing, is provided. The exact differential which is necessary to actuate the valve may be positively controlled by varying the areas which are exposed to the liquid pressure and to the fluid pressure. This type of valve is particularly adaptable for use on a well which has a low liquid standing level and a resultant low pressure within the tubing. Heretofore, it has been necessary in most cases to build up a liquid column within the tubing having a sufficient height to provide a pressure great enough to overbalance the operating pressure of the lifting fluid; or springs have been employed to compensate for pressure. The former method is an impossibility in the case of a well in which the standing level of the liquid is comparatively low. The low liquid level, of course, reduces the pressure and in wells of this kind a flow valve which depends on the pressure of the liquid being greater than the pressure of the lifting fluid for operation, cannot be used. Spring compensated valves have proven impractical because although the spring aids in operation in one direction, it is detrimental when operating in a reverse direction. With the valve herein shown, a liquid pressure of 50 pounds within the tubing could overbalance a pressure of 500 pounds within the well casing by merely changing the areas exposed to the liquid and to the fluid. The valve is automatic in operation and needs no adjustment after its assembly and mounting on the well tubing. It is specifically noted that the device is not to be limited to operating in a low pressure well, but could be used in the usual manner in which a plurality of the valves A would be mounted at various stages in the tubing string. In Figure 1 I have shown two valves mounted in the string but if desired one or any number could be employed depending upon the conditions of the particular well on which the device is used.

In Figures 9 to 11, a modified form of the invention is shown. In this form a more simple structure is disclosed, wherein a single cylinder 55 is employed. The cylinder has its upper end externally screw threaded so as to engage within the openings 23' provided in the underside of a radially projecting boss 24' formed on the tubing 13. The boss 24' is similar to the upper boss 24 in the first form and is provided with an angular port 25' which establishes communication between the interior of the tubing 13 and the upper end of the cylinder 55. The lower end of the cylinder bore 55' is internally screw threaded to receive a closure cap 56. The cap is provided with an axial bore 57 extending entirely therethrough and an annular valve seat 58 is formed at the upper end of said bore. It is noted that the bore of the cap establishes communication between the interior of the well casing and the lower end of the cylinder 55.

The bore 55' of the cylinder is reduced at 55a so as to form an internal annular shoulder 59 within the cylinder. Above the reduced portion 55a the bore is enlarged to form a chamber 60

5 within the upper end of the cylinder. At the upper end of the chamber 60 the bore is again reduced as shown at 55b. An annular valve seat 61 is provided at the upper end of the portion 55b and the extreme upper end 55c of the bore above said valve seat is further reduced to the same diameter as the diameter of the port 25' with which it communicates. The wall of the cylinder 55 has radial ports 62 extending therethrough opposite the chamber 60, whereby fluid under pressure within the well casing may flow through these ports, into the chamber 60 and then upwardly through the angular ports 25' and into the well tubing 13.

10 An elongate tubular piston 63 is mounted to reciprocate within the cylinder 55 and the upper end of this piston is reduced and screw threaded so as to receive the lower end of a head 64. The head has a diameter substantially the same as the diameter of the reduced portions 55a and 55b of the bore of said cylinder, whereby said head has a sliding fit therein. Since the head slides within the reduced portion 55a, it will be obvious that the lower end of the cylinder 63 is movable within the lower end of the cylinder 55. The head 64 is formed with an integral, upwardly extending metering pin 65 which is hollowed out so as to provide a chamber 66 therein. A ball 67 is located within the chamber 66, being adapted to rest on the upper end of the bore 63' of said piston. Inclined ports 68 are provided in the shoulder formed between the head 64 and tapered metering pin 65, whereby a communication is established between the chamber 66 in the upper end of the cylinder 55 and the ball chamber 66. It is noted that the construction of the head 64 and metering pin is such as to provide a cage for the ball 67. The extreme lower end of the piston 63 is provided with an annular flange 69 and a coiled spring 70 surrounds the piston and is confined between this flange and the internal shoulder 59 formed within the cylinder. Manifestly, the spring 70 constantly exerts its pressure to hold the piston in its lowermost position resting on lugs 70' as shown in Figure 9. An annular valve seat 71 is formed within the bore 63' of the piston 63 and this seat is located nearer the lower end of said bore. An elongate stem 72 extends upwardly into the bore 63' and is adapted to have its upper end engaging the seat 71 when the piston is in its lowermost position. The lower end of the stem 72 is formed with an enlarged head 73 which is slidable within the bore 57 of the cap member 56. This head normally has its lower end resting on a snap ring 74 which is inserted in a groove 75 provided within the lower end of the bore 57, whereby the stem cannot fall downwardly from said bore. The head is provided with vertical passages or grooves 76 in its peripheral portion, whereby the fluid below the cylinder and cap may pass upwardly through these grooves and into the bore 57 of said cap, and then finally into the bore 55' of the cylinder 55. When the stem 72 is moved upwardly, as will be explained, the head 73 is arranged to engage the annular valve seat 58 provided at the upper end of the bore 57 of the cap 56 and when said head so engages the seat, the admittance of fluid from the well casing into the lower end of the cylinder 55 is prevented.

15 In operation, assuming the parts to be in the position shown in Figure 9 and before any fluid has been entered into the well casing, it will be obvious that the liquid level in said well casing and in the tubing will be equalized because flow

of the liquid will occur through the angular port 25', chamber 60 and radial port 62 in the upper end of the cylinder 55. When the lifting fluid is introduced into the upper end of the well casing, such fluid will force the liquid in the casing back through the angular port 25' and into the tubing 13. As the liquid flows into the tubing, the gas or other lifting medium will, of course, follow the same to aerate the column and raise the liquid to the surface.

With the parts in the position shown in Figure 9, the fluid pressure may act against the upper end of the piston by entering the chamber 60 and may also act against the lower end of the piston by entering the bore 57 of the cap and then flowing into the bore 55' of the cylinder. This equalizes the pressure on each side of the piston 63 and permits the coil spring 70 to overcome this balanced condition to hold said piston in its lowermost position. It is noted that at this time the stem 72 has its upper end engaging the valve seat 71 within the bore 63' of the piston and fluid may not flow upwardly through said bore. At the same time the fluid pressure within the chamber 60 acts against the upper end of the ball 67 to hold the same seated because the fluid from the chamber may flow through the inclined ports 68 provided in the shoulder between the metering pin 65 and head 64.

As the liquid column within the tubing 13 is lightened the velocity of the fluid flowing through the angular ports 25' commences to increase and as the load continues to lighten the velocity of the lifting fluid increases in accordance therewith. When the velocity of the gas or the lifting fluid through the ports 25' reaches a predetermined point which brings about a lowering of the pressure in the chamber 60, then the constant pressure of the fluid against the lower end of the piston 63 will begin moving said piston upwardly against tension of the spring 70. This upward movement of the piston will, of course, cause the metering pin 65 to enter the reduced upper end 55b of the bore of the cylinder and will also cause the shoulder between said pin and the head 64 to be moved toward the annular valve seat 61 at the upper end of the chamber 60, whereby the flow of fluid to the tubing 13 is decreased. At the same time, as the piston rises, the stem 72 remains seated against the seat 71, said stem following the piston.

As the pressure above the piston, or the pressure in the tubing 13 continues to decrease, the fluid pressure will finally move the upper end of the piston 63 into the reduced portion 55b of the bore and then to its uppermost position which engages the shoulder at the base of the metering pin with the valve seat 61, whereby the flow of lifting fluid into the tubing is entirely cut off. It is noted that as soon as the shoulder at the base of the pin enters this reduced portion, the fluid through the openings 62 is cut off. The stem 72 is of such length that as the piston enters the portion 55b and just before the piston engages the seat 61, the head 73 of said stem engages its seat 58 to shut off the lifting fluid from the interior of the cylinder. This seating of the head prevents further upward movement of the stem 72 and as the piston 63 moves into engagement with the seat, the upper end of the stem leaves its seat 71 within the bore of the cylinder, whereby the fluid trapped below the piston may flow upwardly through the bore 63' to unseat the ball 67. The fluid then flows past the ball and through the inclined ports 68 which are not covered by

the seating of the piston on the seat 61. Thus, the trapped fluid is bled into the tubing from below the piston. As soon as this fluid is bled from the cylinder the spring 70, together with the pressure of the well liquid in the tubing, forces the piston downwardly until the seat 71 within its bore engages the stem which is still held in its raised position by the lifting fluid pressure acting against the bottom of the head 73. At this time,

10 the upper end of the head of the piston is still within the reduced portion 55b of the bore of the cylinder, whereby lifting fluid cannot flow through the ports 68 to the passage 25. The parts will remain in this position (Figure 10) until the 15 pressure of the well liquid within the tubing acting against the top of the piston head overcomes the pressure of the lifting fluid in the casing acting against the underside of the head 73 of the stem 72.

It is noted that at this time the cross-sectional area on which the liquid pressure is exerted is greater than the cross-sectional area of the head of the stem 72, which latter area is acted upon by the lifting fluid pressure within the well casing. Therefore, the liquid pressure, since it acts upon a larger area, need not equal or exceed the pressure of the lifting fluid within the well casing in order to force the piston and stem downwardly to permit another injection of lifting fluid into the well tubing. After the liquid column builds up sufficiently to move the piston 63 downwardly, additional lifting fluid is permitted to enter the tubing 13 to aerate the column therein. As the column is raised and the pressure within the tubing is dropped, the operation of the device is repeated. Thus, it will be seen that the valve shown in Figures 9 to 11 employs the same principle as that of the first form although it is much simpler in construction.

30 40 It is the variation in areas upon which the well liquid acts and upon which the lifting fluid acts that controls the actuation of the valve. By varying these areas, it is possible to accurately determine the differential necessary to operate the device.

In Figures 12 and 13 a modified form of the valve shown in Figures 1 to 9 is disclosed. In this form, the metering pin 47 above the upper piston 42 is omitted and a ball 80 is substituted therefor. A transverse pin 81 extends across the bore 21' of the member 21 to limit the upward movement of the valve. The ball operates exactly as the metering pin, being unseated by the lifting fluid pressure flowing through the upper piston 42 and being seated by liquid pressure from the tubing. The upwardly extending conical pin 41 on the upper end of the lower piston 33 is eliminated and an elongate curved metering pin 82 substituted therefor. The upper end of this pin extends through the opening 31 in the top of the lower cylinder 17 and is secured axially in the underside of the upper piston 42, whereby both pistons move as a unit instead of independently.

65 70 The operation of this form is substantially the same as that of the form shown in Figures 1 to 9. Assuming the parts to be in the position shown in Figure 12, it will be obvious that the lifting fluid pressure will raise the upper piston 42 from its seat. As this occurs, the fluid enters the piston 42 and unseats the ball 80 to enter the tubing. As soon as the piston 42 begins its upward movement, the lower piston 33 will also commence to move upwardly therewith because of their connection through the metering pin 12. At the

same time, upward movement of the pistons causes the pin 82 to move upwardly within the opening 31 to automatically meter the flow of lifting fluid into the tubing. When the upper piston strikes the shoulder 20', the seat 40 engages the opening 31 to cut off the flow of lifting fluid. The operation is then similar to the operation of the first form except that pistons move simultaneously instead of independently.

What I claim and desire to secure by Letters Patent, is:

1. A well flowing apparatus including, a tubular having an influent liquid inlet and an inlet for admitting a lifting fluid, and a valve for controlling the admission of the lifting fluid and actuated by the differential in pressure between the influent in the tubing and the lifting fluid in the casing, said valve exposing different cross-sectional areas to the liquid and fluid when in a closed position, the cross-sectional area which is exposed to the liquid being greater than the cross-sectional area exposed to the fluid.

2. A well flowing apparatus including, a tubular body adapted to be connected with a well tubing and lowered therewith into a well casing, said body having a passage for establishing communication between the casing and tubing, and a valve within the passage for controlling the flow of lifting fluid from the well casing through the passage, said valve being actuated by the differential in pressure between the well liquid in the tubing and the lifting fluid in the casing, the valve exposing different cross-sectional areas to the liquid and fluid when in a closed position, the cross-sectional area which is exposed to the liquid being greater than the cross-sectional area exposed to the fluid.

3. A well flowing apparatus including, a tubular body adapted to be connected with a well tubing and lowered therewith into the well casing, said body having a passage for establishing communication between the casing and tubing, a movable piston for controlling the flow of a lifting fluid under pressure from the casing into the tubing and having a substantially constant cross-sectional area, said piston exposing equal areas on each side thereof to the lifting fluid pressure when the valve is in an open position, whereby the piston is balanced in such position, means for moving the piston to its closed position when the velocity of the lifting fluid reaches a predetermined point, such movement of the piston exposing one side thereof to the well liquid pressure, and a movable member actuated by the well liquid pressure adapted to engage this side of the piston when the same is in its closed position, said member having a larger cross-sectional area than the piston whereby the side of the piston exposed to the well liquid is in effect increased in cross-sectional area.

4. A well flowing apparatus including, a tubular body adapted to be connected with a well tubing and lowered therewith into a well casing, said body having a passage for establishing communication between the casing and tubing, a tubular piston within the body for controlling the admission of a lifting fluid from the well casing through the passage into the well tubing, said body having an opening having a smaller cross-sectional area than the piston in its lower end whereby the lower end of the piston is exposed to the lifting fluid pressure, means for closing the bore of the piston to trap the lifting fluid therebelow, means for moving the piston to its closed position when the velocity of the lifting fluid

entering the tubing reaches a predetermined point, means for closing the opening in the lower end of said body when the piston shuts off the admission of lifting fluid to the tubing, and means associated with the closing means for opening the bore of the piston to permit the escape of lifting fluid trapped below the piston within the body.

5. A well flowing apparatus including, a tubular body adapted to be connected with a well tubing and lowered therewith into a well casing, said body having a passage for establishing communication between the casing and tubing, a movable piston for controlling the flow of a lifting fluid under pressure from the casing into the tubing and having a substantially constant cross-sectional area, said piston exposing substantially equal areas on each side thereof to the lifting fluid when in an open position, whereby the piston is balanced in such position, and a movable member actuated by the well liquid pressure connected to said piston and having a larger cross-sectional area, whereby when the piston has moved to its closed position, the increased cross-sectional area of the member is transferred to the piston through its connection therewith.

6. A well flowing apparatus including, a tubing having a well liquid inlet and an inlet for admitting an auxiliary lifting fluid, a valve for controlling the admission of the lifting fluid into the tubing, said valve exposing substantially equal cross-sectional areas on each side thereof to the pressure of the lifting fluid in the well casing when the valve is in an open position, the valve exposing one side to the well lifting pressure and its opposite side to the well liquid pressure when in a closed position, and a movable piston located in the line of flow of the lifting fluid and exposed to the liquid pressure and having a larger cross-sectional area than the valve, said piston being tubular to permit the lifting fluid to flow therethrough and being arranged to engage one end of the valve when in a closed position, whereby the increased area of the piston is transferred to the valve to open the valve when the liquid pressure reaches a predetermined proportion of the lifting fluid pressure.

7. A well flowing apparatus including, a tubular body adapted to be connected with a well tubing and lowered therewith into the well casing, said body having a passage for establishing communication between the casing and tubing, a valve for controlling the flow of a lifting fluid under pressure from the casing into the tubing and having a substantially constant cross-sectional area, said valve exposing equal areas on each side thereof to the lifting fluid pressure when the valve is in an open position whereby the valve is balanced in such position, means for moving the valve when the velocity of the fluid entering the tubing reaches a predetermined point, and a movable piston within the passage located in the line of flow of the lifting fluid and exposed to the liquid pressure and having a larger cross-sectional area than the valve, said piston being tubular to permit the lifting fluid to flow therethrough and being arranged to engage one end of the valve when in a closed position, whereby the increased area of the piston is transferred to the valve to open the valve when the liquid pressure reaches a predetermined proportion of the lifting fluid pressure.

8. A well flowing apparatus including, a tubular body adapted to be connected with a well tubing and lowered therewith into the well cas-

ing, said body having a passage for establishing communication between the casing and tubing, a valve for controlling the flow of a lifting fluid under pressure from the casing into the tubing and having a substantially constant cross-sectional area, said valve exposing equal areas on each side thereof to the lifting fluid pressure when the valve is in an open position whereby the valve is balanced in such position, means for moving the valve when the velocity of the fluid entering the tubing reaches a predetermined point, a movable piston within the passage located in the line of flow of the lifting fluid and exposed to the liquid pressure and having a larger cross-sectional area than the valve, said piston being tubular to permit the lifting fluid to flow therethrough and being arranged to engage one end of the valve when in a closed position, whereby the increased area of the piston is transferred to the valve to open the valve when the liquid pressure reaches a predetermined proportion of the lifting fluid pressure, and means adapted to enter one end of the bore of the piston for metering the flow of lifting fluid into the tubing.

9. A well flowing apparatus including, a tubing having a well liquid inlet and an inlet for admitting an auxiliary lifting fluid, a valve for controlling the admission of the lifting fluid into the tubing, said valve exposing substantially equal cross-sectional areas on each side thereof to the pressure of the lifting fluid in the well casing when the valve is in an open position, the valve exposing one side to the well lifting pressure and its opposite side to the well liquid pressure when in a closed position, a movable piston located in the line of flow of the lifting fluid and exposed to the liquid pressure and having a larger cross-sectional area than the valve, said piston being tubular to permit the lifting fluid to flow therethrough and being arranged to engage one end of the valve when in a closed position, whereby the increased area of the piston is transferred to the valve to open the valve when the liquid pressure reaches a predetermined proportion of the lifting fluid pressure, resilient means for urging the valve to its open position, and yieldable means for urging the piston toward said valve.

10. A well flowing apparatus including, a tubular body adapted to be connected with a well tubing and lowered therewith into the well casing and having a passage for establishing communication between the casing and tubing, a double valve seat within the passage, a movable valve for controlling the flow of lifting fluid through said passage located below the double seat and adapted to engage the seat to cut off the flow, said valve being of a substantially constant cross-sectional area and exposing equal areas on each side thereof to the lifting fluid pressure when in an unseated or open position whereby the valve is balanced in such position, means for moving the valve from its open position when the velocity of the fluid entering the tubing reaches a predetermined point, and a movable piston located above the double valve seat and exposed to the liquid pressure and having a larger cross-sectional area than the valve, said piston being tubular to permit the lifting fluid to flow therethrough and being arranged to engage one end of the valve when in a closed position, whereby the increased area of the piston is transferred to the valve to open the valve when the liquid pressure reaches a

predetermined proportion of the lifting fluid pressure.

11. A well flowing apparatus including, a tubular body adapted to be connected with a well tubing and lowered therewith into a well casing, said body having a passage for establishing communication between the casing and tubing, a tubular piston within the body for controlling the admission of a lifting fluid from the well casing through the passage into the well tubing, said body having an opening having a smaller cross-sectional area than the piston in its lower end whereby the lower end of the piston is exposed to the lifting fluid pressure, means for closing the bore of the piston to trap the lifting fluid therebelow, means for moving the piston to its closed position when the velocity of the lifting fluid entering the tubing reaches a predetermined point, means for metering the flow of the lifting fluid into the tubing as the piston moves, means for closing the opening in the lower end of said body when the piston shuts off the admission of lifting fluid to the tubing, and means associated with the closing means for opening the bore of the piston to permit the escape of lifting fluid trapped below the piston within the body.

12. A well flowing apparatus including, a tubular body adapted to be connected with a well tubing and lowered therewith into the well casing, said body having a passage for establishing communication between the casing and tubing, a valve for controlling the flow of a lifting fluid under pressure from the casing into the tubing and having a substantially constant cross-sectional area, said valve exposing equal areas on each side thereof to the lifting fluid pressure when the valve is in an open position whereby the valve is balanced in such position, means for moving the valve when the velocity of the fluid entering the tubing reaches a predetermined point, means for engaging one end of the valve when the same is in a closed position and having a larger cross-sectional area than the valve whereby this increased area is transferred to the valve, said last named means being exposed to the well liquid pressure, whereby the valve is opened when the liquid pressure reaches a predetermined proportion of the lifting fluid pressure, and means within the passage for metering the volume of lifting fluid flowing through the passage.

13. A well flowing apparatus including, a tubing having a well liquid inlet and an inlet for admitting an auxiliary lifting fluid, a valve for controlling the admission of the lifting fluid into the tubing, said valve exposing substantially equal cross-sectional areas on each side thereof to the pressure of the lifting fluid in the well casing when the valve is in an open position, the valve exposing one side to the well lifting pressure and its opposite side to the well liquid pressure when in a closed position, means for transferring an increased cross-sectional area to the side of the valve exposed to well liquid whereby the valve is opened by the differential in lifting fluid and well liquid pressures, and means for metering the flow of lifting fluid entering the tubing.

14. A well flowing apparatus including, a tubing having an influent liquid inlet, means for introducing a lifting fluid into the tubing for lifting the influent flowing up the tubing, means for controlling the admission of the lifting fluid and actuated by the differential in pressure be-

tween the well influent in the tubing and the lifting fluid in the well casing, said means exposing different cross-sectional area to the liquid and fluid, the cross-sectional area which is exposed to the liquid being greater than the cross-sectional area exposed to fluid, whereby when the pressure of the liquid reaches a predetermined proportion of the pressure of the lifting fluid, said means is actuated, and means for metering the flow of lifting fluid entering the tubing.

15. A well flowing apparatus including, a tubing having an influent liquid inlet and an inlet for admitting a lifting fluid, a valve for con-

trolling the admission of the lifting fluid and actuated by the differential in pressure between the influent in the tubing and the lifting fluid in the casing, said valve exposing different cross-sectional areas to the liquid and fluid when in a closed position, the cross-sectional area which is exposed to the liquid being greater than the cross-sectional area exposed to the fluid, and movable metering means associated with the valve for metering the flow of lifting fluid entering the tubing.

CHARLES S. CRICKMER.
